UNITED STATES PATENT OFFICE.

EDWARD S. FORD, OF HOXTON, COUNTY OF MIDDLESEX, ENGLAND,
ASSIGNOR TO OSCAR UHLMAN, OF BAVARIA, GERMANY.

VENDING-MACHINE.

SPECIFICATION forming part of Letters Patent No. 398,245, dated February 19, 1889.

Application filed October 16, 1888. Serial No. 288,250. (No model.)

To all whom it may concern:

Be it known that I, EDWARD SAMUEL FORD, a subject of the Queen of Great Britain, residing at 35 Upper John Street, Hoxton, in the 5 county of Middlesex, England, have invented certain new and useful Improvements in Coin-Operated Vending-Machines, of which the following is a specification.

My invention has reference to apparatus in 10 which by the insertion of a prescribed coin mechanism is freed or actuated, so as to deliver or release for delivery an article or commodity in exchange for said coin; and it relates more particularly to apparatus which 15 comprise a goods carrier or drum divided into compartments and rotated by means of a spring to an amount corresponding with one compartment when an escapement is temporarily freed through the action of the inserted 20 coin.

My invention provides an improved coin-slide so constructed that any coin of less diameter than that prescribed—which is, for example, a five-cent piece—falls out before 25 reaching the chute or guide for conducting the coin to the point where it is to act upon the releasing mechanism. It also provides a separator or divider in connection with the drum, which, as the latter rotates, enters the 30 goods-compartments successively and separates the outermost article therein from the other article or other articles, so that the drum can be supplied with two or more articles in each compartment and deliver them 35 separately, whereas in apparatus of this description as heretofore constructed the whole contents of a compartment, whether one article or more, have been delivered at once. This separator or divider is capable of adjustment, so as to adapt the apparatus to articles 40 of different thickness.

In the accompanying drawings, Figure 1 is a front elevation of the apparatus. Fig. 2 is a similar view, but with the door, which constitutes the greater portion of the front, removed. Fig. 3 is a transverse section on line 3 3 of Fig. 1, looking to the left. Fig. 4 is a section on the same line as Fig. 3, but looking to the right, and with the drum-spring 45 and escapement removed. Fig. 5 is a section

on line 5 5, Fig. 4, showing the coin-slide. Figs. 6 and 7 are respectively a side view and a plan of a distance-piece used in adjusting the separator or divider.

a is the outer box or case of the apparatus, 55 which in the preferred form is rectangular, as shown.

b is a door at the front of the box, secured thereto by hinges *c c*, and fitted at *d* with a lock of any ordinary construction. 60

In the preferred construction the central portion of the door is cut away, the opening thus formed being backed up with a sheet of glass, *e*, which is held at top and bottom by clips or holders *ff*. The goods in the drum-compartments can thus be seen from the outside. The part of the glass which is in front of that part of the drum which extends from the center to the inner walls of the compartments is preferably silvered on the inside, so 65 as to give a neat appearance to the apparatus. In the door *b* is the coin-slit *h*, which is just large enough to allow of the insertion of the prescribed coin. This slit is inclined, as shown, to correspond with the sidewise incline of the coin-slide, hereinafter described. In the door *b* is also the goods-outlet *i*, with flanged shelf *j*, for arresting the article which falls from the drum, and which is conducted 70 by the guideway, hereinafter described, to 75 said outlet *i*.

k is the coin-slide. It is inclined toward the right hand, as shown, so that the coin inserted through the slit *h*, which has the same inclination, may enter the slide in an inclined 85 position, as seen in Fig. 5, in which *l* represents the coin. The lower edge of the coin runs upon the ledge or flange *m* of the slide. In the side of the slide is cut an opening, *n*, of such width between its upper and lower 90 edges that, while a coin of the prescribed size will run along the slide with its upper part leaning against the side of the slide above said opening *n*, a coin of smaller diameter will not be supported by the slide above said opening, and will therefore fall sidewise with its upper part entering the opening. In so doing it will rock over the lower margin or shoulder, *n'*, of the opening, (which is lower than the center of gravity of the smallest coin 95 100

that may be inserted in the apparatus,) whereby the lower part of the coin will be thrust to the left, as shown in dotted lines in Fig. 5, and its lower edge will consequently slip off 5 over the edge of the ledge *m*, and the coin will therefore fall down into the box *o* below without reaching the coin-chute. The coin-slide *k* is inclined from front to back, as clearly seen in Fig. 4, so as to cause the coin to run 10 to the back end and enter the coin-chute.

p is the coin-chute, down which the coin (of the prescribed size) on reaching the back end of the slide *k* falls, so as to strike and depress the end of the lever *q*, after which the coin 15 drops into the box *o*. The other end of lever *q* bears against one branch, *r*, of an anchor, the other arm, *r'*, of which normally takes into the teeth of the escapement *s*. The escapement is fixed on the arbor of the 20 drum *t*, on which is a spring, *u*, wound up by rotating the drum.

It will be readily understood that each time the lever *q* is acted upon by a falling coin it will by pushing up the arm *r* temporarily release the arm *r'* from the escapement *s*, so that the drum will move round the distance allowed by one tooth of the escapement and be then again caught and retained by the arm *r'*. The drum *t* has at its periphery 30 radial compartments *v v*, for containing the goods or articles to be delivered. They are shown as containing cigarettes, three in each compartment. The drum moves within a fixed casing, *w*, at one part of which is an 35 opening, *x*, above an inclined guideway, *y*, leading to the outlet *i*, already described. Consequently as each compartment *v* comes in turn to the opening *x* the contents, so far as they are not prevented by the separator or 40 divider, hereinafter described, will fall through the opening *x*, be conducted by the guideway *y* to the outlet *i*, and be presented on the flanged shelf *j*.

I will now describe the separator or divider, 45 which prevents the delivery of more than one article at a time from a compartment. This separator is composed of stationary fingers *z*, (of which two are shown, but one will answer if sufficiently broad,) which project at the 50 proper height through the side partition of each compartment *v* as this comes round to the opening *x*. The partitions are formed with openings *A A*, Fig. 3, so as to clear or pass the fingers. As will be seen on reference to Fig. 53, the height of the fingers is such that they come between the outermost article in the compartment and the other article or articles therein, and thereby hold up such other article or articles until the compartment has passed 60 the opening *x*. Therefore only the outermost article falls through this opening and is delivered.

In order to make the separator or divider adjustable, so as to adapt the apparatus for 65 delivering articles of different thickness—such, for instance, as cigars—only two of which can be placed in a compartment capable of

holding three cigarettes, I adopt the following arrangement: I fix the fingers *z* to or form them in a piece with a plate, *B*, which I secure 70 by a mill-headed screw, *C*, to the block *y'*, in which the guideway *y* is formed. Between the block *y'* and the plate *B* is a spring, *y'*, which tends to push the plate away from the block, the plate pivoting on the pin *D*. For the 75 smallest size of goods to be delivered—say cigarettes—the plate *B* is screwed up to the full extent against the block. When, on the other hand, the apparatus is required to hold and deliver larger articles—say cigars—the 80 screw *C* is unscrewed, and the spring then pushes the plate *B* outward, so that the fingers *z* rise. A distance-piece, *E*, (shown separately in Figs. 6 and 7 and in dots in Fig. 3,) is then pushed through a guide, *L*, so as to 85 enter between the plate *B* and block *y'*, and the screw *C* is then screwed up so far as the piece *E* will allow. This has the effect, by slightly lowering the fingers from the position to which they had risen, of bringing them to 90 the proper height for separating the two cigars in each compartment as it comes round. The piece *E* is forked or slotted, as seen in Fig. 6, to allow the screw *C* to pass through it.

In order to prevent the spring *u* from being overwound, I mount on a horizontal arbor a piece, *F*, having as many teeth *G* (say three) as the maximum number of articles that a compartment of the drum is intended to hold. On the face of the piece *F* is a pin or stud, *H*. On the drum *t* is an arm, *J*, which, upon the completion of every revolution of the drum, comes against one of the teeth *G* and moves the piece *F* round to the extent of one tooth. When at the end of three revolutions of the 105 drum the piece *F* has been moved to the extent of three teeth, the pin *H* comes against a stop, *K*, and prevents further movement of the drum, and therefore any further winding of the spring *u*. As the drum rotates in the reverse direction during the discharge of the goods from its compartments, the arm *J* acts on the piece *F* in the contrary direction, and thereby puts it in position to allow of the spring *u* being again wound up.

What I claim, and desire to secure by Letters Patent, is—

1. In an automatic coin-free or coin-actuated apparatus, a coin-slide comprising an inclined side against which the coin leans and a bottom ledge or flange upon which the edge of the coin runs, said inclined side having an opening of such height that a coin of smaller diameter than that of the prescribed coin will not be supported by the inclined side, but 120 will fall into said opening, and of such width that its lower side shall form a shoulder beneath the center of gravity of the coin, over which shoulder the coin on falling into the opening shall rock, so that its lower edge will 125 be thrust off the ledge and the coin will drop out on the side opposite to said opening, substantially as set forth.
2. In an automatic coin-free or coin-actu-

ated apparatus for delivering goods in exchange for coin, the combination, with a goods carrier or drum having radial goods-compartments around its periphery and caused to rotate to the extent of one compartment for each action of the apparatus, of a separator or divider which enters the goods-compartments as they successively reach or approach the delivery-outlet and separates the outermost article in the compartment from the other article or articles therein, whereby only one article is delivered from a compartment containing more than one article, substantially as set forth.

15 3. The combination, with the rotating drum t , having radial goods-compartments v , formed with openings A.A in their partitions,

and with the fixed casing w , having an opening, x , of the stationary fingers z , arranged to enter the openings A in the sides of the compartments, whereby the latter are caused to clear or pass said fingers, substantially as set forth.

4. The combination of the plate B, having the fingers z , with the adjusting-screw C and 25 distance-piece E, substantially as and for the purpose set forth.

In witness whereof I have hereunto signed my name in the presence of two subscribing witnesses.

EDWARD S. FORD.
